EXPANDING EARTH ANCHOR

Filed June 7, 1928

INVENTOR:
JASPER BLACKBURN.

By Edward G. Longan
ATTORNEY.

UNITED STATES PATENT OFFICE

JASPER BLACKBURN, OF WEBSTER GROVES, MISSOURI

EXPANDING EARTH ANCHOR

Application filed June 7, 1928. Serial No. 283,470.

My invention relates to improvements in expanding earth anchors, and has for its primary object an earth anchor which is provided with extensible plates or flukes, which 5 can be driven outward simultaneously so as to extend beyond the body portion of the anchor and into the solid earth surrounding the anchor.

A further object is to construct an earth 10 anchor having flukes or plates which will be expanded laterally by means of a cone, the cone being adapted to be forced downward for expanding the plates by blows of a tampering implement.

15 A still further object is to construct an expanding earth anchor in such a manner that the anchor rod may be removed therefrom when desired so as to leave no projection above the earth and without the necessity of 20 removing the entire anchor.

In the drawings:

Fig. 1 is a plan view of my anchor with part of one of the flukes or expansible plates broken away showing the slot which guides 25 the flukes or plates;

Fig. 2 is a section taken on the line 2—2 of Fig. 1 with the expanding cone in position;

Fig. 3 is a plan view of my device with the flukes or plates expanded;

30 Fig. 4 is an enlarged fragmental section taken on the line 4—4 of Fig. 2; and

Fig. 5 is a side elevation of my device when fully expanded.

In the construction of my device I employ 35 a plate 6, which is provided on its underneath surface with a plurality of radially extending projections 7. These projections are made hollow as illustrated in Figs. 2 and 5, the purpose of which will be explained in detail later. The plate 6 is also provided with slots 8, which communicate with the interior of the hollow projections 7 although these slots do not extend to the outer edge of the plate but are so arranged as to leave a portion 40 9 closing the outer end of the slot. The inner end of the slot is enlarged as indicated by the numeral 10 so as to receive the head 11 of a lug carried by the expanding plates or flukes 12. These lugs are formed on the under face of the expanding plates or flukes and

have a reduced portion 13 which fits within the slot 8. In this manner the flukes or plates 12 are held against vertical displacement but may be moved outward radially.

The flukes or plates 12 are also provided with an up-raised portion 14, which fits over the portion 15 of an adjacent fluke or plate so that these plates can be fully collapsed and when in collapsed position will occupy no greater area than the plate 6.

The plates or flukes 12 are also provided with upwardly projecting wedge-shaped portions 16 which have their inner edges 17 inclining inwardly and downwardly. The inner edges or faces 17 of the projection 16 are 65 designed to be contacted with by the conical member 18 so that when this member is driven downward it will have a tendency to force the flukes or plates 12 outward radially and simultaneously.

The conical member 18 is loosely and slidably mounted on the anchor rod 19, which is provided on its upper end with an eye 20 through which a guy wire or strand can be secured.

In order to further strengthen the plate 6 I make use of ribs 21 which are formed integral with the plate and extend between the projections 7. The anchor rod 19 is screw threaded at its lower end as indicated by the 80 numeral 22 so as to receive the nut 23. The nut 23, however, is prevented from turning by means of a projection 24 formed integral with the bottom of the plate 6.

The conical member 18 is preferably provided with radially extending ribs 25 so that the member may be made hollow but still have sufficient rigidity thereby saving considerable in the amount of material used without sacrificing any strength.

Both the conical member and the plate 6 may be further lightened by forming openings therein at suitable points, these openings, however, being so positioned that while saving weight of material, do not in any way 95 reduce or affect the strength of the anchor.

From my construction it will be readily seen that the various flukes or expansion plates can be placed in position on the plate 6, then the anchor rod 19 secured in position 100

by means of the nut 22, after which the conical member 18 can be dropped over the anchor rod prior to securing the eye 20 on its upper end.

5 After the device has been thus assembled, the anchor is ready to be placed in position.

The first step necessary, of course, is to bore a hole in the ground to the required depth and of the necessary diameter to receive the plate 6, the flukes or plates 12 being so positioned that their periphery does not exceed the periphery of the plate 6. The anchor is then lowered into the hole and by means of any suitable tamping tool or bar the conical member is driven downward. As this member 18 is driven downward it must necessarily ride on the inclined faces or edges 17 of the wedged projections 16 and, inasmuch as they are formed integral with 10 the expanding plates, such driving down of the conical member 18 will result in forcing the plates or flukes 12 away from the center, this forcing down done simultaneously so that all flukes or plates will move outward 15 radially and in a plane parallel to the plate 6 simultaneously. This driving or forcing out of the plates or flukes 12 cause them to become imbedded in the undisturbed ground around the bored hole in which the plate 20 is inserted and this entering into the solid ground of the flukes 12 is further enhanced by sharpening the edges of the flukes as indicated by the numeral 26.

My present anchor is an improvement on 35 Patent No. 1,407,920, granted to me on February 28th, 1922 and, although similar in construction, differs essentially in details, especially in view of the fact that in my present construction all of the expanding flukes 40 or plates are forced out simultaneously and naturally to the same extent whereas in the patent aforementioned it was necessary to force out each plate independently; consequently there was always a possibility of one 45 plate being forced out farther than the others from the center of the anchor thereby setting up uneven strains in the supporting plate, but with my present structure this is obviated because all upward strain will be 50 evenly distributed.

Having fully described my invention, what I claim is:—

1. An expanding earth anchor comprising a plate, a plurality of flukes having integral 55 upstanding inclined projections carried by said plate, said flukes arranged for horizontal radial outward movement, an anchor rod carried by said plate, and a conical member slidably mounted on said anchor rod, said member adapted to be driven downward by an implement and contact with said projections for moving said flukes outward simultaneously.

60 2. An expanding earth anchor comprising a circular plate, radially extending guide-

ways formed in said plate, flukes having wedge-shaped upstanding portions mounted on said plate, means carried by the underside of said flukes and extending into said passageways for preventing the accidental separation of said flukes and plate, an anchor rod extending upwardly from said plate and surrounded by said flukes, a conical member slidably mounted on said anchor rod, said conical member adapted to simultaneously spread said flukes outward horizontally from the center of the plate when said conical member is forced down.

70 3. An expanding earth anchor comprising a plate reinforced on its underside, a plurality of overlapping flukes having integral upstanding inclined projections carried by said plate, said flukes arranged for radial outward movement, an anchor rod carried by said plate, and a conical member slidably mounted on said anchor rod, said member adapted to be driven downward by an implement and contact with said projections for moving said flukes outward simultaneously 75 and in a horizontal direction.

80 4. An expanding earth anchor comprising a plate reinforced on its underside, radially extending guideways formed in said plate, overlapping flukes having wedge-shaped upstanding portions mounted on said plate, means carried by the underside of said flukes and extending into said passageways for preventing the accidental separation of said flukes and plate, an anchor rod extending upwardly from said plate and surrounded by 85 said flukes, a conical member slidably mounted on said anchor rod, said conical member adapted to spread said flukes outward from the center of the plate simultaneously and parallel thereto when said conical member is forced down.

90 5. An expanding earth anchor comprising a plate, a plurality of flukes having upstanding projections carried by said plate, said flukes arranged for radial outward movement, an anchor rod carried by said plate, and a member having a downwardly and inwardly inclined edge slidably mounted on said anchor rod, said member adapted to be driven downward by an implement and contact with said projections for moving all of 95 said flukes outward and parallel to said plate simultaneously.

100 In testimony whereof I have affixed my 110 signature.

JASPER BLACKBURN.
